UNITED STATES PATENT OFFICE.

JAMES H. BROTHERS, OF NEWARK, NEW JERSEY, ASSIGNOR TO THE RAIL JOINT COMPANY, A CORPORATION OF NEW YORK.

INSULATED RAIL-JOINT.

No. 873,492.

Specification of Letters Patent.

Patented Dec. 10, 1907.

Original application filed March 22, 1907, Serial No. 363,921. Divided and this application filed September 7, 1907. Serial No. 391,847.

To all whom it may concern:

Be it known that I, JAMES H. BROTHERS, a citizen of the United States, residing at Newark, in the county of Essex and State of New Jersey, have invented certain new and useful Improvements in Insulated Rail-Joints, of which the following is a specification.

This invention relates to the art of insulated rail joints, and has special reference to certain novel and practical improvements therein designed to provide a solid metallic bearing support at the under sides of the rail heads, and also to maintain an effective insulation throughout the joint.

15 To this end the invention contemplates an insulated rail joint wherein no insulation is interposed directly beneath the heads of the rails and the metallic bars of the joint next to the same, thereby allowing the heads of the rails to take a solid, direct bearing on the said joint bars, and permitting of the provision of such a bearing or bearings for the insulating members or material as to more effectually safeguard the same from flowing, 20 or cutting out, under the pressure of the load imposed on the rails by the passing trains.

Hence, a distinctive object of the invention resides in a construction which obviates the necessity of placing insulating material 30 directly between the rail sides and heads and the adjacent joint bars, and at the same time providing a novel arrangement of discontinuous filler members for each rail, and continuous splice bars for both rails, whereby 35 the bearing area for the insulating material is increased to a greater extent than the area of the under sides of the rail heads.

In other words, the invention provides a novel construction, combination, and arrangement of parts serving to increase, in a practical manner, the bearing area for the insulating material, and decrease the fiber strain, thus enabling the material to better withstand the load imposed.

45 With these and many other objects in view, which will more readily appear as the nature of the invention is better understood, the same consists in the novel construction, combination, and arrangement of parts hereinafter more fully described, illustrated, and claimed.

A few preferred embodiments of the inven-

tion are shown in the accompanying drawings, in which:

Figure 1 is a side elevation of one design of rail joint embodying the present invention. Fig. 2 is a cross sectional view of the joint shown in Fig. 1, the line of section being taken on the line 2—2 of Fig. 1, showing one rail end and the ends of the discontinuous 55 filler members therefor in elevation. Fig. 3 is a cross sectional view of a modified form of joint embodying the present invention, the line of section being adjacent to one of the joint bolts. Fig. 4 is a similar sectional 60 view of another modified form of joint embodying the invention.

Like references designate corresponding parts in the several figures of the drawings.

A distinctive feature of the present invention resides in an insulated joint having outer splice bars, discontinuous inner filler members or filler bars next to the rails, and insulation between the splice bars and the filler members, the latter being arranged to engage 70 the under sides of the rail heads and having flanges, the area of which flanges is greater than the area of the under sides of the rail heads, whereby an increased bearing area is provided for the insulation with a consequent 75 reduction of the fiber strain. This thought may be embodied in several forms of construction, and is well exemplified by the design of joint shown in Figs. 1 and 2 of the drawings. This joint includes in its general 80 organization the service rails 1 and 2, the continuous splice bars 18, the discontinuous 85 filler members or bars 19, and the joint bolts 20. The oppositely arranged splice bars 18 extend the full length of the joint between 90 the two rails, and the filler members or bars 19 are located at the inner sides of the splice bars and take a direct bearing against the rails and beneath the under sides 5 of the rail heads. The filler members are not co-extensive in length with the splice bars, and therefore do not extend the full length of the joint, as each rail end has fitted thereto a 95 pair of separate discontinuous filler members 19 arranged respectively upon opposite sides thereof and terminating at the end of the rail, as plainly shown in Figs. 1 and 2 of the drawings. All of the said filler members are 100 preferably duplicates in design and con-

struction, and each of the same is illustrated as provided at its upper edge with a bearing head 21 for engagement at the under side of the rail head, and at its lower edge is provided with an outwardly deflected inclined foot flange 22 overlying the rail base, and having formed integral therewith the outstanding reinforcing and spiking flange 23, and the bottom horizontal base section or 10 base plate 24 arranged beneath and supporting the rail base. In the form of joint shown in Figs. 1 and 2, each filler member 19 has its upright portion or girder in the form of a channeled bar which produces at the upper 15 edge thereof not only the bearing head 21, but also an outwardly extending bearing projection or flange 25 whose bearing face is of greater area than the area of the under side of the rail head, and is designed to bear 20 on the upper outturned flange 26 of the side insulating sheet 27. This side insulating sheet 27 is interposed between the filler member 19 referred to and the splice bar 18 which registers in the channel of the filler 25 member, and said insulating sheet 27 is also provided at its lower edge with a lower outturned flange 28, said flanges 26 and 28 being interposed respectively between the top and bottom edges of the splice bar and 30 the opposing inclined faces of the filler member.

By reason of the construction described, it will be observed that while each filler member or bar takes a solid metallic bearing 35 under the head of the rail, the same presents a bearing surface for the insulation of greater area than the area of the under side of the rail head, hence providing an increased bearing area for the insulation with 40 a consequent reduction of the fiber strain.

In the form of joint just described, the same is completed by the joint bolts 20, and to provide for a proper bolt insulation any of the well known bolt insulating expedients 45 may be employed, such for instance as insulating bushings or sleeves 14 lining the bolt holes in the filler members and splice bars, and the insulating washers 15 separate from or integral with the outer ends of the bushings or sleeves 14 and arranged between the outer faces of the splice bars and the backings washers 16 which are disposed, as usual, at the inner sides of the heads and nuts of the bolts. In connection with the insulation of 55 the joint, it is to be further observed that by reason of the discontinuity of the filler members, that is, the employment of filler members for each rail (which filler members terminate at the end of said rail), the joint can 60 be effectively insulated by having a one-end insulation only therefor, that is, having the insulating material applied to the parts associated with one of the rails instead of being associated with both.

65 In Figs. 1 and 2 of the drawings, the

joint is illustrated as having the side insulating sheets arranged in connection with the filler members of both rails, and the insulation of the joint is completed by the employment of the end insulation or end insulating 70 post 29 interposed between the rail ends and also between the ends of the discontinuous filler members 19.

A still further modification of the invention is shown in Fig. 3 of the drawings, 75 which illustrates a joint comprising the usual service rails, the outer continuous splice bars 36, the discontinuous filler members 37, and the joint bolts 38, the latter being provided with insulating means such as described. Each filler member 37 is illustrated as provided at its upper edge with a bearing head 39 for engagement beneath the rail head, and at its lower edge with a foot flange 40 overlying the rail base. 80 Also, the splice bar 36 is illustrated as having its upright or girder member of a channel formation so as to produce at the upper edge of the splice bar an outturned angularly disposed bearing flange 42 arranged 85 parallel with, and lying opposite, the off-standing bearing flange 41 projected outwardly from the upper portion of the filler member. Furthermore, the splice bar 36 is formed with a lower flange member 43 overlying the foot flange 40 of the filler member. 90 The said lower flange member 43 has formed integrally therewith the outstanding reinforcing and spiking flange 44, and the bottom horizontal base section 45, which latter 100 underlies the rail base. A side insulating sheet 46 is interposed between the splice bar and the filler member, and is provided at its upper edge with a top flange 47 interposed between the flanges 41 and 42 of the 105 filler member and splice bar, and at its lower edge the side insulating sheet is formed with an apron extension 48 extending over the outer edges of the foot flange 40 and the rail base flange and having continued therefrom a bottom insulating section 49 lying between the base section 45 and the rail base. It will be observed that the formation of the individual filler members 37 provides an extended bearing surface for the 115 insulation, which is of greater area than the area of the contact between the filler members and the under side of the rail head.

The invention is further exemplified by the modification shown in Fig. 4 of the 120 drawings. The joint illustrated in this figure of the drawings is similar in its general design, and essential features, to the joint shown in Fig. 3, and embodies the usual service rails, the continuous splice bars 50 and 67, the discontinuous filler members 52 and the joint bolts 53^a, the latter being provided with suitable insulating means, preferably such as described. Each filler member 52 is provided at its upper edge with a bearing 125

130

head 53 for engagement beneath the rail head, and at its lower edge with a foot flange 54 overlying the rail base. The said bearing head 53 at the upper edge of each filler member is formed with an outwardly extending bearing projection or flange 55 whose bearing face 56 is of greater area than the area of the under side of the rail head, and in the form of the joint shown in Fig. 4 of the drawings, the said offstanding bearing projection or flange 55 of the filler member 52, at the outside of the rail, is adapted to overlie an out-turned angularly disposed bearing flange 57 deflected outwardly from the upper edge of the continuous splice bar 50 located at the outer side of the joint. It will be observed that the said outer splice bar 50 is provided with an upright girder member of a channel formation producing the said upper bearing flange 57 and the lower flange member 58 overlying the foot flange 54 of the filler member 52. The said lower flange member 58 of the outer splice bar 50 has formed integrally therewith the outstanding reinforcing and spiking flange 59, and the bottom horizontal base section 60. In this embodiment of the invention, a distinctive feature thereof resides in the fact that the integral base section 60, carried by the outer splice bar 50, is of a width coextensive with, or greater than, the width of the rail base so as to extend entirely under the rail base to the inside of the rail, as plainly shown in Fig. 4 of the drawings. To provide for an effective insulation of the parts coöperating with the said outer splice bar 50, a side insulating sheet 61 is interposed between said splice bar and the filler member 52, which side insulating sheet is formed at its upper edge with a flange extension 63, interposed between the bearing projection or flange 55 and the bearing flange 57. At its lower edge, the said insulating sheet is formed with an apron extension 64 extending over the outer edges of the foot flange 54 and the rail base, and having continued therefrom a bottom insulating section 64^a lying between the full width base section 60 and the rail base.

Another distinctive feature of the design of joint, shown in Fig. 4 of the drawings, 50 resides in associating with the filler member 52, arranged at the inside of the rail, a channel or equivalent splice bar 67 having interposed between the same and the adjacent filler member 52, a side insulating sheet 68 55 of substantially the same form as the corresponding insulating sheet shown in Fig. 2 of the drawings.

Other modifications will suggest themselves to those skilled in the art, and it will 60 be understood that various changes in the form, proportion, and minor details of construction may be resorted to without departing from the spirit or sacrificing any of the advantages of the invention. 65

I claim:

1. In a rail joint, the rails, continuous splice bars and discontinuous filler members, said filler members being arranged at the sides of each rail and having a bearing 70 against the under sides of the rail heads and also having portions overlying the splice bars.

2. In a rail joint, the rails, continuous splice bars and separate discontinuous filler 75 members, said filler members being arranged at the sides of each rail and having a direct bearing against the under sides of the rail heads, said filler members having portions overlying the splice bars which are of greater 80 area than the area of the under sides of the rail heads.

3. In an insulated rail joint, the rails, continuous splice bars, separate discontinuous filler members arranged at the sides of each 85 rail and having a bearing against the under side of the rail heads and on top of the splice bars, and insulating material interposed between the filler members and the splice bars.

In testimony whereof I hereunto affix my 90 signature in the presence of two witnesses.
